UNITED STATES PATENT OFFICE.

ALFRED M. LANE, OF ST. LOUIS, MISSOURI, ASSIGNOR TO MONARCH METAL WEATHER STRIP COMPANY, OF ST. LOUIS, MISSOURI, A CORPORATION OF MISSOURI.

WEATHER-STRIP.

1,134,209.

Specification of Letters Patent.

Patented Apr. 6, 1915.

Application filed January 26, 1914. Serial No. 814,297.

To all whom it may concern:

Be it known that I, ALFRED M. LANE, a citizen of the United States, and a resident of the city of St. Louis and State of Missouri, have invented a new and useful Improvement in Weather-Strips, of which the following is a specification.

This invention relates to weather strips and more particularly to that form of weather strip which is especially adapted to be applied to the meeting rails of coöperating upper and lower sliding window sashes and to casements or swinging window sashes.

The principal objects of this invention are to form a simple and efficient construction which will make a weather-tight joint such as will exclude drafts and prevent dust from entering the space between a window and its frame; to shape and arrange the parts of the weather strip so as to facilitate the installation; to provide a weather strip which will not have its efficiency impaired by any swelling or shrinking of the window sash or by any other derangement of the relative position of the sash and frame whether due to wear and usage or any other cause, and which will prevent any rattling of the sash.

Other objects of my invention and advantages resulting from the construction I employ will more fully appear hereinafter.

In general, according to my invention, the members forming the weather strip are made of thin resilient sheet metal, preferably of some suitable non-corrosive material, and each member is adapted for attachment to one of two meeting parts, such as the frame and sash of a window. One member is formed with a sealing tongue, which, in the closed position of the window, engages in a receiving pocket formed as a part of the other member and the mouth edges of this pocket are held by the resiliency of the parts in close contact with the sealing tongue.

The invention consists in the construction and in the arrangement and combination of parts hereinafter more fully set forth.

In the accompanying drawing, which forms part of this specification and in which like reference characters refer to like parts throughout the different views, Figure 1 is a cross-section of a weather strip embodying

my invention showing it applied to the side 55 of a casement window, the casement window frame and sash being shown in horizontal section, and the window being partly opened; Fig. 2 is a view similar to Fig. 1, the window being closed; Fig. 3 is a view of a 60 weather strip embodying a modified form of my invention showing it applied to the bottom of a casement window, the casement window frame and sash being shown in vertical section and the window being partly 65 opened; Fig. 4 is a view similar to Fig. 3, the window being closed; Fig. 5 is a cross-section of a weather strip embodying another form of my invention showing it applied to the meeting stiles of a pair of casement window sashes, one window being 70 partly opened; and Fig. 6 is a view similar to Fig. 5 with the window closed.

In the drawing, a portion of the window frame is shown and is designated by the 75 numeral 1. One member A of the strip is formed by a piece of resilient sheet metal which extends along the inner or window face of the window frame 1. One marginal portion 2 of said member, reinforced by a 80 sharp rebend is tacked or otherwise suitably fastened to the window frame. From this marginal portion 2 the major part 3 of the member is bent so as to extend away from the face of the frame, and the remaining 85 part 4 is extended substantially parallel with the face of the frame. The other marginal portion of the member A is bent upon itself so as to form a pocket 5, the free edge of which is bent to form a roll or bead 6, 90 which normally lies in contact or nearly in contact with the main body of the member.

The window sash 7 is rabbeted to accommodate the other member B of the weather strip, and this member B coöperates with 95 the member A to form the weather-tight joint. The member B extends along the window sash 7 and one marginal portion 8, reinforced by a sharp rebend, is tacked or otherwise suitably fastened to the face of 100 the rabbet adjacent the vertical face of the sash. From this marginal portion 8 the member is bent to extend into the rabbet and rebent to form a groove 9; and the remaining portion is rebent sharply along 10 the outer edge of the groove 9 to form a sealing tongue 10 and is thence extended along the outer face of the sash, to which

it is fastened by tacks or by any other suitable fastening means.

When the window is closed, the sealing tongue 10 of the member B engages the inwardly bent portion 3 of the member A and depresses the main body of the member A. This guides the sealing tongue 10 between the body of the member A and the bead 6 into the pocket 5. The bead 6 engages the bottom of the groove 9. The joint formed in this construction is characterized by three lines of contact between the members. The mouth edges of the pocket 5 press resiliently upon both faces of the sealing tongue 10 and thus form two lines of contact. The bead 6 seats tightly against the bottom of the groove 9 and forms the third line of contact.

Under normal conditions the portion 3 of the member A extends away from the frame 1 toward the window sash to such a degree that, when the window is closed, the portion 3 is pressed back toward the frame and is thereby placed under tension so as to bear firmly against the outer face of the sealing tongue 10. This not only makes the joint tight by the pressure against the outer face of the sealing tongue 10, but also prevents the window from rattling. In many cases the fit of the window sash in its frame is affected either by shrinking, swelling or warping of its parts or by wear; and the window sash has the position of its top, bottom or sides or of some intermediate part displaced relative to the frame so that there is not the normal space between the frame and these parts.

In my invention, any part of the member B may move either toward or away from the frame 1 to a large extent and still the sealing tongue 10 will be guided into the pocket 5. This insures that the members A and B will always be placed in their operative position when the window is closed regardless of the fit of the window sash in its frame. Also, the joint formed by the members A and B is not affected by the position of the window sash 7 relative to the frame 1 and the same three lines of contact are maintained. This will be understood from an examination of Fig. 2. As the window sash 7 moves away from or toward the frame 1 the sealing tongue 10 will always maintain two lines of contact with the mouth edges of the pocket 5, and the bead 6 will rock in its seat at the bottom of the groove 9 and maintain the third line of contact. The member A is placed so as to make the joint which it forms with the member B at the outer or weather edge of the window so as to prevent the outside air, moisture or dust from even partially entering. In weather strips, the joint between the parts not only serves to protect against moisture, but also acts to receive and partially retain moisture; and to protect all the exposed wood against the attack of

such moisture, the member B is extended so as to cover the faces of the rabbet in the sash.

According to the preferred way in which my weather strip is installed, the members A and B are extended around the top and sides of the window; and it is possible that some moisture, cold air, or weather elements may pass downwardly along the sides of the window.

For the bottom of the window the modified form of weather strip shown in Figs. 3 and 4 is especially adapted. In this modified form, the member A' is mounted in a rabbet in the window sash 7. One marginal portion 11 of the member A', reinforced by a sharp rebend, is tacked to the window sash. From this marginal portion 11 the major part is bent to form an arch 12 extending away from the face of the rabbet. From the line of contact of the free edge of this arch with the face of the rabbet the member A' is thence extended and bent upon itself to form a pocket 13 having its free edge rolled to form a bead 14. The member B' is substantially Z-shaped and one part 15 is tacked or otherwise suitably secured to the window sill 1'. From this part 15 the member is extended upwardly and then outwardly, substantially parallel with the top face of the sill 1', to form the horizontally extending portion 16 which is upwardly curved and forms a sealing tongue. This modified form of weather strip operates in substantially the same manner as the strip shown in Figs. 1 and 2, and the same three lines of contact are secured.

By comparing Figs. 2 and 4, it can be seen that the joint formed at the bottom of the sash, which is shown in Fig. 4, is disposed farther from the outside or weather edge of the window than the joint formed at the sides and top of the sash which is shown in Fig. 2. This assures that all of the cold air, moisture, or other weather elements that may pass downwardly along the sides of the window sill be guided outside of the joint at the bottom. The window sill 1' is cut away to form a face 17 slanting downwardly from the outer edge of the attached part 15 of the member B'. This serves not only to drain away any moisture which may accumulate at the bottom joint of the window, but also makes it necessary for any moisture which may reach the bottom joint to pass upwardly along this downwardly extending incline.

The form of weather strip illustrated in Figs. 5 and 6 is specially adapted for use in connection with the meeting stiles of casement windows. The casement window sashes 18 and 19 are usually provided with matched rabbets 20 and 21 respectively. A pocket member A'', substantially the same in form as the pocket member A' shown in

Figs. 3 and 4, has its marginal portion 22 tacked or otherwise suitably fastened to the inner face of the rabbet 20. The marginal portion 22 of this member A'', which is 5 fastened to the sash frame, is not reinforced by a sharp rebend, as is the edge of the member A', because the small space desirable will not accommodate such a reinforcement. The tongue member B'' is the 10 same as the tongue member B shown in Figs. 1 and 2 and is similarly disposed in the rabbet 23 in the face of the stile 19. The marginal edge 24 of the member B'' is tacked to the outer face of the stile 19, and the reinforced marginal edge 25 is tacked to the 15 vertical face of the rabbet 23.

Obviously, the different forms of my invention are not limited in their use to the particular parts of the window to which I 20 have shown and described them as being applied, and while I have shown my invention in connection with a casement window, it may, if desired, be also applied to the horizontal meeting rails of sliding window 25 sashes or to any other construction where the conditions are favorable. Therefore, I do not wish to be limited to the particular construction and arrangement that I have shown and described.

30 What I claim as my invention is:

1. In a weather strip, a member formed of a resilient strip of metal and comprising a marginal portion adapted to be fastened to a window frame, an intermediate portion 35 bent at an obtuse angle to said marginal portion to extend away from the face of the window frame when fastened thereto, an opposite marginal portion bent to form a pocket, the marginal edge of said opposite 40 marginal portion being formed with a bead, lying close to said opposite portion, and a second member coöperating with said first named member and comprising a marginal portion adapted to be fastened to a window 45 sash, an intermediate portion bent to form a groove adapted to receive said bead, and a tongue adapted to engage said intermediate portion of said first named member and be guided between said bead and said opposite 50 site marginal portion into said pocket.

2. A weather strip comprising two coöperating members adapted for attachment, one to each of two relatively movable parts, one member being resilient and mounted 55 with its body portion extended normally across the path of movement of the other member, the free marginal portion of said first named member having a pocket, the mouth edges of said pocket being held resiliently close to one another, one of said 60 mouth edges being bent to form a bead, and said second named member being made of relatively stiff material and formed with a groove adapted to receive the bead on said 65 first named member, one side of said groove

forming a relatively rigid tongue adapted to engage the body portion of said first named member and be guided into said pocket.

3. The combination with the sides of a 70 window frame and a sash mounted to swing in said frame, of a member attached to each one of said sides and formed of a relatively flexible and resilient strip secured to said side near one marginal edge, the opposite 75 marginal portion of said strip being bent upon itself to form a pocket having its free edge beaded and bent to lie close to said opposite marginal portion, the body portion of said strip extending away from the face 80 of the window frame, and a second member made of relatively stiff material and secured near its marginal edges to a side of said sash, said strip having its intermediate portion bent to form a groove adapted to receive said bead and a tongue extending from one edge of said groove and adapted to engage the body portion of said first named member and be guided into said pocket.

4. A member of a weather strip formed of a resilient piece of metal, and comprising a marginal portion adapted to be attached to a window frame, an intermediate portion 95 extending at an obtuse angle to said marginal portion, a pocket at the edge of said intermediate portion having one of its sides arranged parallel to said marginal portion and its other side formed with a beaded edge which normally lies close to the edge of 100 said first named side of said pocket.

5. In a weather strip, the combination of two coöperating members, one member comprising a resilient metal strip fastened near one longitudinal margin thereof and having 105 the other longitudinal marginal portion thereof bent upon itself to form a pocket, said strip being bent longitudinally between the bottom of said pocket and said first-mentioned margin, said pocket having a 110 relatively narrow throat, and the other member comprising a relatively stiff metal strip having a tongue adapted to enter said pocket.

6. A weather strip comprising two coöperating members, adapted for attachment one to each of two relatively movable parts, one member being resilient and mounted with its body portion spaced from the movable part to which it is attached and normally extending across the path of movement of the second member, the free marginal portion of said first named member being bent upon itself to form a pocket, and having its edge rolled to form a bead normally lying close to said body portion, said second member having a tongue adapted to engage said body portion and be guided into said pocket.

7. In a weather strip, a member comprising

ing a resilient metal strip having one longitudinal marginal portion thereof adapted to be fastened to a window frame, and having the other longitudinal marginal portion 5 thereof bent upon itself to form a pocket whose longer axis extends substantially parallel to said window frame, the edge portion of said marginal portion being bent into a bead, said bead being held resiliently close 10 to said strip, said strip being bent longitudinally between said first-mentioned marginal portion and the bottom of said pocket.

8. In a weather strip, the combination of 15 two coöperating members, one member comprising a resilient metal strip having one marginal portion thereof bent upon itself to form a pocket, said pocket having a relatively narrow throat, the edge portion of 20 said marginal portion being bent upon itself to form a bead, which constitutes one of the lips of said pocket, the other member comprising a relatively stiff metal strip bent to form a groove, one side of said groove being adapted to enter said pocket and to bring

said bead into engagement with the bottom 25 of said groove.

9. In a weather strip, a member made of a strip of metal bent to form a groove and a tongue at the edge of said groove, said member being attached to one of two relatively 30 movable parts, a second member made of a resilient strip of metal and mounted on the other one of said two relatively movable parts with its body portion spaced from said movable part and normally extending across 35 the path of movement of said first named member, said second member being bent upon itself to form a pocket, the tongue of said first named member being adapted to engage said body portion of said second 40 member and be guided into said pocket.

Signed at St. Louis, Missouri, this 23rd day of January, 1914.
